DESIGN FOR A BOUDOIR SLIPPER

Stella M. Groff, Santa Ana, Calif.

Application February 28, 1945, Serial No. 118,185

Term of patent 7 years

(Cl. D7—7)

To all whom it may concern:

Be it known that I, Stella M. Groff, a citizen of the United States and resident of Santa Ana, county of Orange, State of California, have invented a new, original, and ornamental Design for a Boudoir Slipper, of which the following is a specification, reference being had to the accompanying drawing, forming a part thereof.

Fig. 1 is a side elevational view of a boudoir slipper showing my new design.

Fig. 2 is a top plan view.

Fig. 3 is a bottom plan view of the slipper.

I claim:

The ornamental design for a boudoir slipper, as shown.

STELLA M. GROFF.
